UNITED STATES PATENT OFFICE.

STARR H. BARNUM, OF NEW HAVEN, AND TOWNSEND H. SOREN, OF WEST HARTFORD, CONNECTICUT, ASSIGNORS TO THE BIGELOW COMPANY, OF NEW HAVEN, CONNECTICUT.

WATER-TUBE BOILER.

Application filed August 4, 1922. Serial No. 579,778.

Our invention relates to steam boilers and more particularly to those wherein provision is made for pre-heating the feed water prior to its introduction into the boiler proper by means of heat extracted from the hot gases after they have passed through the main portion of the boiler.

While we have shown and will describe our invention as applied to a water-tube boiler wherein headers in the form of drums are interconnected by a series of parallel tubes to form boiler units, it will be understood that the invention is not necessarily limited to an installation of this type but certain features thereof may be advantageously employed in other types of boilers as well.

It will be recognized that if the feed water delivered to the boiler is pre-heated to some extent by heat extracted from the gases after they have passed through the boiler proper, which heat would otherwise be lost, the efficiency of the installation will be greatly increased and purification of the feed water prior to its entry into the boiler will be effected. In addition the temperature stresses in the units will be lessened, as also will water hammer effects.

One object of our invention, therefore, is to provide a water-tube boiler embodying an improved arrangement or combination of parts for heating the feed water prior to its delivery to the main part of the boiler by means of heat absorbed from the escaping gases in such a manner that a maximum amount of heat will be absorbed by the entering feed water from such gases.

Still another object of the invention is to provide for the distribution of gases by a proper arrangement of baffling that the amount of resistance to the passage of the gases, or draft loss, will be reduced to a minimum.

Our invention further resides in the provision of improved connections between the economizer and boiler proper and in other features inherent in the structure and combination of parts to be hereinafter described and claimed.

In the accompanying drawings:

Fig. 1 is a sectional elevational view of an installation provided with an economizer embodying our improvements;

Fig. 2 is a top plan view of the same;

Fig. 3 is a sectional view on line 3—3 of Fig. 1;

Fig. 4 is a fragmentary sectional view on line 4—4 of Fig. 3;

Fig. 5 is a sectional elevational view similar to Fig. 1 showing a modified form of our invention;

Figs. 6, 7 and 8 are views similar to Fig. 5, each showing a further modification of our invention.

In Figs. 1 to 4 of the drawings is illustrated a boiler having a setting A, which may be provided with a rearward extension B within which the preheater or economizer may be installed.

The boiler proper consists of one or more front sections or banks 10 and one or more rear sections 11. These sections or banks are each made up of a plurality of units, each of which consists of an upper drum 12 and a lower drum 13 connected by a plurality of substantially parallel straight tubes 14. The drums 12 may be termed the steam drums, as the generated steam collects therein and passes from them through ducts 15 to the main steam drum 16. Between the units is provided the baffling 17, which causes the hot gases to pass directly over the pipes 14 in thin streams, so that the greatest possible amount of heat will be extracted from the gases passing from the furnace.

A stoker of any preferred type may be used and the boiler may be arranged to burn any desired type of fuel. In the drawing the stoker is shown more or less diagrammatically at 19.

A super-heater 20 may be provided for the steam having a connection 21 with the main steam drum and a connection 22 with the steam pipe 23 through which the steam is carried to the turbine or engine.

The lower drums 13 are provided with blow-out headers 24 from which run blow-off pipes 25 through which the boiler may be cleaned.

Rearwardly of the installation which has just been described is an economizer or pre-heater in the part B of the boiler setting, which comprises a section made up of a plurality of units which are similar in number and construction to the boiler units previously described. Each of these units consists of an upper drum 26, and a lower

drum 27, the two drums being connected by a nest of straight tubes 29. The lower drums 27 are provided with water connections 30 through which the feed water is 5 introduced into the economizer. The upper drums 26 are provided with pipes 31 which enter the steam drums of the adjacent boiler units through the usual water connections 31^a, the ends of these pipes being disposed 10 in this instance below the level of the water in the latter drums. The feed water after being pre-heated is thus introduced into the upper drums of the rearmost boiler section through the pipes 31.

15 The boiler setting B is provided with baffles 32 and 33, which causes the hot gases escaping from the boiler to pass over the economizer tubes a plurality of times prior to its delivery to the flue 34, as shown by 20 the arrows in Fig. 1. The sections of the economizer are also provided with baffles 35 by which the hot gases will be prevented from passing between two adjacent tube units but will be caused to flow through the 25 units themselves by which the gases will be broken up into thin streams and the greatest possible amount of heat will be absorbed by the water in the tubes.

It will be obvious that with this construction the feed water will be introduced to the 30 economizer through the lower drums 27 where the coolest gases within the boiler setting are to be found just prior to their leaving the boiler through the flue 34. The 35 water passes upwardly through the pipes 29 into the upper drums 26 and is gradually heated prior to its entry into the sections of the boiler proper through the tubes 31. The 40 water also passes to the boiler proper at the point where the coolest gases are found and the carrying forward of this idea throughout the boiler causes the water to be heated gradually and in this manner undue temperature stresses are eliminated. Also the 45 baffles 32 and 33, which may be placed about the economizer section in any desired arrangement or in any suitable number cause the greatest possible amount of heat to be absorbed from the gases prior to the 50 escape thereof through the flue 34.

The main steam-drum 16 is horizontally arranged at the top of the boiler, and the front units are inclined forwardly and upwardly with their upper drums in front of the main steam-drum, their lower ends being just to the rear of the masonry wall at the rear of the fire-box. The rear units are somewhat shorter than the front ones, and vertically disposed, with their lower drums 55 connected with those of the front units and their upper drums located rearwardly of the main steam-drum and connected therewith in the manner previously described. Associated with the nests of tubes forming 60 parts of the front units are the baffles 17

extending throughout the greater part of the length of said nests of tubes and arranged between each nest and the adjacent one transversely of the boiler, as shown in Fig. 3, with similar baffles between the end 70 nests and the adjacent walls of the setting. The result of using these cross baffles is that the gases passing from the fire-box in a generally upward and rearward direction pass directly through the respective nests 75 of tubes substantially throughout their length. In passing through a nest of tubes in the spaces between the individual tubes the gases are divided up into thin streams, which accelerates the heat absorption. The 80 deflection of the gases in passing through the front units is lateral only, and from these sections the gases pass directly in a generally rearward and slightly upward direction to the nests of the rear units, 85 which have similar baffles, extending throughout their length, so that the deflection of the gases is only in a lateral direction, and here the division of the gases into thin streams is repeated. The rearward 90 travel of the gases to a substantial distance beyond the lower portions of the rear units is prevented by the wall 51 which separates the rear units from the economizer units to a certain extent. This wall 51 extends upwardly a distance corresponding to a considerably part of the length of the tube nests of the rear boiler units and the 95 economizer units between which it is interposed, and provides an exit for the gases 100 issuing from the rear unit nests only at the upper rear part of the boiler. This exit is further restricted by a baffle 52 vertically arranged and extending downwardly from points adjacent the upper drums of the rear 105 boiler units, behind the tube nests, toward but slightly in front of the upper edge of the separating wall 51. The result is that the gases which have passed upwardly and 110 rearwardly over the front and rear sections of the boiler units pass over the upper end of the wall 51 in a confined stream after having passed over the outer surfaces of the tube nests in thin streams over a very 115 large area. As the gases pass over the upper edge of the wall 51 they move rearwardly through the nests of economizer tubes, in the upper portions of those nests, and then forwardly again through the nests at a somewhat lower elevation, and then rearwardly again through the nests at a still lower elevation, until eventually the flue is reached. It will be seen, therefore, that in 120 passing in a generally downward direction over the tubes of the economizer nests in which the water is rising, the gases are confined laterally so as to pass approximately horizontally and rearwardly between the individual tubes of each nest, while being prevented from passing between the adjacent 125 130

nests, and between the nests at the ends and the adjacent walls of the setting. At the same time the gases are forced to travel in a generally downward direction by the substantially horizontal baffles 32, 33, as already explained. This combination of the vertical and horizontal baffles assures the passage of all the gases over the economizer tubes and their division into thin streams, with rapid heat transfer, and at the same time it is required that the gases will repeatedly pass forwardly and rearwardly so that after heating a portion of the nest at a certain elevation they next heat a cooler portion at a lower elevation, and so on. Thus a maximum amount of heat is absorbed, but, at the same time, by the arrangement described, the draft loss is not injuriously increased, because of the length of the open spaces between the tubes and the relatively short path of the gases from the furnace to the stack.

In Fig. 5 of the drawings, a modification is shown wherein the rearward extension B of the boiler setting is not separated from the boiler proper and the baffling about the economizer is dispensed with, the gases passing directly over the economizer sections in the same manner in which they pass over the sections of the boiler proper.

In Fig. 6 of the drawings we have shown a construction wherein the upper drums 40 of the economizer are placed in a relatively low position and the water therefrom may pass into the lower portion of the adjacent drums 12 of the boiler proper below the water level through the pipes 41.

In the modification shown in Fig. 7, the upper drums 42 of the economizers are provided with steam spaces and in this instance these drums are provided with a connection 43 to the steam spaces of the upper drums 12 as well as a connection 44 which enters these drums below the water level therein.

A further modification is shown in Fig. 8 of the drawings wherein a plurality of economizer sections are shown, each section of which may be formed similar to the single section described in connection with the modification shown in Figs. 1 to 4. In this instance horizontally disposed baffles 46, 47 and 48 may be provided and a vertical baffle 49 extends for some distance between the sections, so that the gases will be properly circulated about the pipes prior to their escape from the furnace through the flue 50, which in this instance, may be arranged toward the upper part of the setting. The gases entering the economizer chamber pass above the baffle 46 and are deflected downwardly by the baffle 49 to pass through the pipes of the first section again and below the baffle 47. They then pass through the lower portion of the pipes of the second section and are deflected by the baffle 48 against

the rear side of the baffle 49 where they are again turned through the pipes of the rear section of the economizer and pass out through the flue.

It will be obvious that as provision is made for the admission of the water supply to the economizer at one end thereof and for the passage of the water to the boiler at the other end, the flow of this water through the economizer will be in one general direction, i. e., toward the boiler. Moreover, this advantageous feature will be further aided by the fact that the hot gases first reach the economizer adjacent the end from which the water passes to the boiler and thus the hottest gases from the boiler first reach the hottest water in the economizer. This, of course, also aids in keeping the flow of water through the economizer always in the same direction, and does not tend to create a flow in the opposite direction which would cause circulation in the economizer pipes, and causes the greatest possible amount of heat to be extracted from the hot gases by the water.

It will also be evident that the settling of any impurities or scum to the bottom of the economizer will be facilitated by the fact that there is little or no circulation of the water therein, and as the lower drums of the economizer and the tubes may be readily cleaned, this is another advantageous feature of our improved construction.

While we have shown and described some forms of our invention, it will be understood that the same is not to be limited to the exact details shown, but is capable of many modifications and variations within the spirit of the invention and within the scope of the appended claims.

What we claim is:

1. In a water-tube boiler, a horizontal steam-drum, upwardly and forwardly inclined units arranged with their upper ends in front of and in communication with said steam-drum, each consisting of upper and lower headers and a nest of tubes connecting said headers, units vertically disposed at the rear of said steam-drum and having their upper ends connected therewith, said rear units each consisting of upper and lower headers and a nest of interconnecting tubes, the lower headers of said front units being connected to those of the rear units, a wall rising at the rear of said rear units and extending throughout a considerable portion of the length of the nests of tubes of said units but terminating short of the level of the upper tube ends of said units, economizer units arranged at the rear of said wall parallel to said rear units, and each consisting of upper and lower headers and a nest of tubes interconnecting said headers, means for introducing feed water into the lower

headers of said economizer units, means for connecting the upper headers of said economizer units with the upper ends of the adjacent rear units, longitudinally extending 5 baffles between the adjacent nests of front and rear units to cause the gases to pass in a generally upward and rearward direction through the different nests substantially throughout their length, said wall confining 10 the egress of said gases so that it takes place adjacent the upper portions of the nests of economizer tubes, baffles extending longitudinally between the economizer nests substantially throughout their length so as to restrict 15 the flow of gases to the spaces between the individual tubes of the nests, and means for causing the gases passing through the economizer nests in thin streams to take a generally downward course over approximately 20 the entire length of the economizer tubes.

2. In a water-tube boiler, a horizontal steam-drum, upwardly and forwardly inclined units arranged with their upper ends 25 in front of and in communication with said steam-drum, each consisting of upper and lower headers and a nest of tubes connecting said headers, units vertically disposed at the rear of said steam-drum and having their 30 upper ends connected therewith, said rear units each consisting of upper and lower headers and a nest of interconnecting tubes, the lower headers of said front units being connected to those of the rear units, a wall 35 rising at the rear of said rear units and extending throughout a considerable portion of the length of the nests of tubes of said units but terminating short of the level of the upper tube ends of said units, economizer 40 units at the rear of said wall parallel to said rear units, and each consisting of upper and lower headers and a nest of tubes interconnecting said headers, means for introducing feed water into the lower headers of said 45 economizer units, means for connecting the upper headers of said economizer units with the upper ends of the adjacent rear units, the front and rear units of the boiler being provided with longitudinally extending baffles 50 which cause the gases to pass in a generally upward and rearward direction through the different nests with lateral deflection around the tubes, said wall confining the egress of said gases so that it takes 55 place adjacent the upper portions of the nests of economizer tubes, baffles extending longitudinally of the economizer nests so as to restrict the flow of gases to the spaces between the individual tubes of the nests, means 60 for causing the gases passing through the economizer nests in thin streams to take a generally downward course over approximately the entire length of the economizer tubes, and a baffle extending downwardly 65 from the upper parts of the rearmost boiler

units adjacent the nests of their tubes and at the rear thereof and cooperating with the upper end of said separating wall in confining to a restricted egress space the gases passing to the economizer units. 70

3. In a water-tube boiler, a steam-drum, a plurality of units associated therewith and connected thereto, including vertically disposed units each comprising upper and lower headers and an interconnecting nest of tubes, substantially vertical baffles separating said nests from each other substantially throughout their length so as to provide for the passage of the gases through each nest in a wide stream subdivided by the individual tubes 80 of the nest, a wall at the rear of said units extending throughout a considerable portion of the length of the tubes but terminating short of their upper ends, a plurality of economizer units of similar formation to said first named units located at the rear of said wall and to which the escaping gases flow over the top of said wall, substantially vertical baffles interposed between the nests of economizer tubes substantially throughout their length so as to cause the gases to pass rearwardly through the nests after passing over said wall at the upper portions of said tubes, and substantially horizontal 85 baffles for causing the gases passing between the economizer tubes to be deflected downwardly and then forwardly and rearwardly again through said economizer tube nests, means for introducing feed water into the lower headers of said economizer units, and connections between the upper headers of said units and the adjacent boiler units. 90

4. In a water-tube boiler, an upper steam-drum, a plurality of units associated therewith and connected thereto, including vertically disposed units at the rear of said boiler, each comprising upper and lower headers and an interconnecting nest of tubes, said nests being of substantially cylindrical shape, substantially vertical baffles interposed between the cylindrical nests of tubes and between the end nests and the setting walls and extending substantially throughout the length of said nests so as to permit the passage of the gases transversely through 110 the nests throughout their length but prevent the gases from passing between the nests, whereby such gases are divided laterally into thin streams by the tubes, a wall rising at the rear of said units so as to allow 115 space between it and the rear nests of tubes, and extending upwardly along said tubes but terminating short of their upper ends, a plurality of economizer units located at the rear of and spaced from said wall substantially parallel to said other units, and likewise consisting of upper and lower headers and cylindrical nests of interconnecting tubes, substantially vertical baffles interposed between the nests of economizer tubes 120 130

so as to permit the gases passing over the top of said wall to move through the economizer tube nests but prevent said gases from passing between said nests, with lateral 5 deflection of said gases by the individual economizer tubes, means for introducing feed water into the lower headers of said economizer units, means connecting the upper headers of said economizer units with 10 the upper headers of the rear boiler units, and means for causing the gases passing over the wall and through the economizer tube nests to be deflected downwardly after such 15 passage and then forwardly and rearwardly again through said economizer tube nests until they reach the lower end portions of 20 said tubes.

5. In a water-tube boiler, a main steam-drum, a plurality of boiler units connected therewith, each comprising upper and lower headers and a nest of tubes interconnecting said headers, said units disposed in a substantially upright position, an upright wall 25 at the rear of said units terminating short of the upper ends of their tubes so as to confine the escape of gases passing around the tubes to the space above the top of the wall, econo-

mizer units parallel to said boiler units at the rear of said wall and having upper connections with said units, each of said units 30 comprising upper and lower headers and a nest of interconnecting tubes, said units so disposed that the escaping gases passing over the wall first strike the upper portions of the tubes of said economizer units, means for supplying feed water to the lower ends of 35 said units, vertical baffles interposed between the respective nests of economizer tubes and extending substantially throughout the 40 length of said economizer tubes so that substantially all the gases are forced to pass through the nests in thin streams, and substantially horizontal baffles associated with 45 said economizer units for causing the gases passing through the upper portions of the economizer tube nests to be deflected downwardly and then forwardly through the nests and then rearwardly again through 50 said nests before reaching the lowermost portions of the economizer tubes.

In witness whereof, we have hereunto set our hands on the first day of August, 1922.

STARR H. BARNUM.
